(57) **CLAIM**

The ornamental design for a solar tonneau cover, as shown and described.

DESCRIPTION

FIG. 1 is a front view of a solar tonneau cover showing our new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a bottom, front perspective view thereof; and,

FIG. 8 is a top, rear perspective view thereof.

The broken lines shown represent the portions of the solar tonneau cover that form no part of the claimed design.

1 Claim, 6 Drawing Sheets
